SIGNAL MEANS FOR TAXIMETERS

Original Filed July 29, 1929

UNITED STATES PATENT OFFICE

1,952,722

SIGNAL MEANS FOR TAXIMETERS

Jerome Mackin, New York, N. Y.

Application July 29, 1929, Serial No. 381,766

Renewed August 16, 1933

2 Claims. (Cl. 200—16)

This invention relates to new and useful improvements in illuminating signal means for taximeters.

The invention has for an object the provision of a device of the class mentioned which is of simple durable construction, desirable in use and efficient in action, and which can be manufactured and sold at a reasonable cost.

The invention proposes illuminating signal means for indicating whether a taxicab is occupied or unoccupied for advising prospective passengers. Quite often when a person is nearly directly in front of a taxicab or in the night, it is difficult to see whether the cab is occupied or 15 vacant.

The invention further proposes a casing attached on a taximeter and having a plunger de-pressible by the handle of the meter flag when the meter flag is in a raised position, a key holding the plunger against rotation and arranged for a slight amount of further depression relative to its depressed position, as determined by the handle of the flag, to disengage the key and permit rotation to another position, and in the 20 first position upon depression contacts close a circuit thru one colored light indicating that the taxi carries no passengers, and upon extension contacts close another circuit thru a different colored light indicating that the taxi carries a 25 passenger, and in the second position inoperative in both depressed and extended positions.

For further comprehension of the invention, and of the objects and advantages thereof, reference will be had to the following description 35 and accompanying drawing, and to the appended claims in which the various novel features of the invention are more particularly set forth.

In the accompanying drawing forming a material part of this disclosure:—

40 Fig. 1 is a fragmentary perspective view of a taxicab equipped with the signal means.

Fig. 2 is a fragmentary vertical sectional view of the taximeter and the signal control means.

45 Fig. 3 is a horizontal sectional view taken on the line 3—3 of Fig. 2, and provided with schematic wiring.

Fig. 4 is a view similar to Fig. 3 but showing the device with the meter flag lowered.

50 Fig. 5 is a vertical sectional view taken on the line 5—5 of Fig. 4.

Fig. 6 is an enlarged detail fragmentary sectional view taken on the line 6—6 of Fig. 4.

Fig. 7 is a fragmentary sectional view taken on the line 7—7 of Fig. 3.

55 Fig. 8 shows a modified form of plunger.

The reference numeral 10 indicates generally a taxicab provided with a taximeter 11 having a flag 12 arranged for being turned downwards as shown in Fig. 1, when the cab is occupied, and turned upwards when unoccupied. A pair of 60 indicating lamps 13, 14 are shown mounted upon the roof of the taxi and are arranged for indicating whether the cab is occupied or not as hereinafter described. These lights may be arranged in a suitable covering or housing. The light 13 preferably should be green and arranged to light when the cab is occupied and the light 14 yellow and arranged to light when the cab is unoccupied.

A switch casing 15 is attached upon the top of the taximeter 11. The flag 12 is provided with a 70 handle portion 16 connected with the flag shaft 17. A plunger 18 is slidably mounted within the casing 15 and is arranged parallel with the shaft 17 and directly over it. The front end of the plunger rod extends from the front of the casing 75 and is provided with a head 19.

The plunger rod 18 is provided with a peripheral recess 20 intermediate of its ends which is engaged by an insulation ring 21. An expansion spring 22 is coaxially mounted on the plunger 80 rod and acts between the casing and the insulation ring for normally urging the plunger outwards. A collar 23 projects from the plunger rod and limits its outward position.

A contact clamp 24 is mounted upon the insulation ring 21 and electrically connects with an insulated loose wire 25. This wire electrically connects with a cable 26 extending from the casing and connected with one of the terminals of a battery 27. A front stationary contact 28 is 90 mounted within the casing and is engageable by the contact clamp 24 in the extended position of the plunger 18. A rear stationary contact 29 is mounted within the casing and is engageable by the contact clamp 24 in the depressed position of the plunger arm. A cable 30 electrically connects with the contact 28 and with the green lamp 13 and in series with the battery 27. Another cable 32 electrically connects with the contact 29 and with the yellow lamp 14 and is in 100 series with the battery 27 and in parallel with the cable 30.

The flag handle 16 is provided with an arcuate lateral arm 33 arranged to engage against the head 19 when the flag is moved from its down to 105 its up position. In Fig. 3 the handle 16 of the flag is shown against the head 19 so that the plunger is in its retracted position. A key 34 projects from the front portion of the plunger 18 and engages in a keyway 35 formed in the 110

front face of the casing 15 for limiting the plunger against rotation. The plunger may be manually slightly further depressed from the position as seen in Fig. 3 so that the key 34 disengages from the keyway 35, then the plunger may be rotated and released for permitting the key 34 to engage in a second keyway 36 formed in the front face of the casing 15.

In operation of the device, the key 34 is engaged in the keyway 35. In the down position of the flag, its handle 16 does not act against the head of the plunger so that the spring 22 may force the plunger to its out position. In this position the contact clamp 24 engages against the stationary contact 28 and closes the circuit thru the green lamp 13 indicating that the cab is occupied. After the passenger leaves the cab, the driver turns the flag to a vertical position and the handle 16 then depresses the head 19 so that the contact clamp 24 engages the contact 29 and closes the circuit thru the yellow lamp 14 which indicates the vacant position of the cab. The driver may disconnect the lamps from operation whenever this is found desirable by manually forcing the head 19 completely inwards and turning the plunger 18 so that the key 34 engages the keyway 36. In this condition of the plunger the contact clamp 24 cannot reach and engage the contacts 28 and 29.

In Fig. 8 plunger 18' is shown to be extendible in order to make it adaptable to different types of taximeters. When head 19 is set to the right position, the telescopic portion of plunger 18' is locked by set screw 18a.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

45

1. In a switch of the class described, a switch casing, one face of said casing having a circular hole therein with two grooves in the periphery of said hole, a plunger rod slidably mounted through said hole and rotatable therein, a contact piece fixed to said rod and extending in a plane parallel with the axis of said rod, a flat contact piece fixed within said casing adjacent the face through which the rod passes, a second flat contact piece fixed within said casing remote from the rod supporting face, the contact surfaces of said flat contact pieces both being in the same plane and parallel with the axis of said rod, resilient means normally urging said rod to its extended position, a key fixed to said rod and extending longitudinally thereof engageable in one of said grooves and maintaining the rod-held contact piece in a plane of reciprocation the same as the plane of the fixed contact pieces, said key being positioned a sufficient distance away from the outer end of the rod to allow disengagement from the said groove when the rod is fully depressed, whereby the rod may be rotated to a position to positively hold the rod-held contact piece in a plane of reciprocation out of the plane of the fixed contact pieces by engaging the key in the second groove.

2. In a switch of the class described, a switch casing, a plunger rod slidably and turnably mounted in said casing, means in said casing to guide said rod in its reciprocatory movement in either of two angular positions, a contact member mounted on said rod, a pair of contacts mounted in said casing at spaced positions in the path of movement of the contact member in one of the angular positions of said rod, said contacts lying out of the path of movement of the contact member in the other angular position of the rod, said rod guiding means terminating short of the end of the reciprocatory movement of the rod, whereby said rod may be turned when at one end of its movement into guided relationship with either of said guiding means.

JEROME MACKIN.
